DENTAL FLASK

Julius J. E. Baumgarten, Portland, Oreg.

Application September 25, 1933, Serial No. 690,832

2 Claims. (Cl. 18—33)

This invention relates generally to the art of dentistry, and particularly to a dental flask for use in connection with the forming of plates.

The main object of this invention is to provide a flask which will accommodate itself to a wide range of work and which can be easily operated with a minimum expenditure of time and in which the molded objects can be easily removed from the flask without endangering the product or marring the flask itself.

These, and other objects, will become more apparent from the specification following as illustrated in the accompanying drawings, in which:

Fig. 1 is a vertical section through the bottom of the flask showing the trial plate set in plaster.

Fig. 2 is a vertical section showing the top of the flask secured in position.

Fig. 3 is a side elevation of the flask showing a portion of the top broken away in section disclosing the plastic material filling the flask and projecting above the top thereof.

Fig. 4 is a view similar to Fig. 3 showing the cap in place with the excess materials escaped from the vents.

Fig. 5 shows the flask separated along a line between its upper and lower portions with a blank in position.

Fig. 6 is a view similar to Fig. 5 showing the flask after heat and pressure have been applied and the upper and lower portions locked together.

Fig. 7 is a perspective view of the cap.

Fig. 8 is a perspective view of the upper part of the flask.

Fig. 9 is a perspective view of the bottom part of the flask.

Fig. 10 is a perspective view of the locking ring.

Fig. 11 is a section taken along the line 11—11 in Fig. 12.

Fig. 12 is a section taken along the line 12—12 in Fig. 6.

Similar numbers of reference refer to similar parts throughout the several views.

Referring in detail to the drawings, the device consists of three principal elements, namely a bottom, a top and a cap which will be described separately.

The bottom 15 of the flask has a cup-shaped recess 16 formed therein and its flat bottom 17 is provided with outlet openings 18 for the escape of excess plastic material 19 in which is first mounted the trial plate 20 whose teeth 21 project upwardly (as shown in Fig. 2).

The plastic bottom 15 is provided on its under side with a locking ring 22 (shown in Fig. 10) which ring is provided on its outer edge with a

plurality of lugs 23, each of which is provided with a keyhole slot 24. Each lug 23 is provided with hook ends 25 for a spanner wrench 26 by means of which a limited amount of rotation may be applied to the locking ring 22. Rotation of the ring 22 is limited by means of a screw 27 which is threaded into the flask bottom 15 and occupies the space between the cutaway portion 28 of the locking ring 22.

The ring 22 is held against the face 29 of the bottom 15 by the rolled edge 30. The face 29A of the ring 22 is provided with inclined portions 31 directly across each of the slots 24, the deeper portion of the inclined face being nearest the large portion of the keyhole slot 24.

The bottom 15 is provided with radial lugs 32 through one end of each of which extends a tapering hole 33. The lugs 32 constitute striking points to facilitate the opening of the flask.

The top 34 of the flask is in the form of a hollow cone whose interior 35 is substantially the same as the recess 16 of the bottom 15. The top 34 is provided with lugs 36 on its exterior surface, in which lugs are mounted the tapering pins 37 each of which is provided with opposite side notches 38. The head 39 of each pin 37 is adapted to pass through the enlarged portion 40 of the slots 24, while the notched portion 41 of the pins 37 can pass through the narrow portions of the slot 24. The smaller end 42 of the flask top 34 is provided with an external thread 43 which is preferably of the cut-away type (as shown in the drawings) to expedite the application and removal thereof.

The cap 44 consists of a circular plate provided with a flange 45 on whose inner side are formed the threads 46 which are adapted to engage the threads 43 of the top 34. The cap 44 is provided with openings 47 for the escape of surplus plastic materials 48. The cap 44 is also provided with out-turned lugs 49 by means of which the cap may be tightened or loosened with relation to the top 34.

It is desirable to provide outlet openings 50 along the parting line 51 of the flask and also to form a depression 52 in the outer wall of the top 34 for use in connection with dry heat.

The operation of the device is as follows: It is assumed that the trial plate 20 has been formed and that it is now desired to produce a permanent plate therefrom. The bottom 15 of the flask is placed in the position shown in Fig. 1 and filled with a plastic material 19 in which the trial plate 20 is mounted, as shown. The next step is to place the flask top 34 in place (as shown in Fig. 55

2) locking same in position by rotating the locking ring 22 by means of the spanner wrench 26, or by tapping same.

The surface 53 of the plastic material 19 is coated with a suitable material to prevent it from adhering to the plastic material 48, which is now inserted into the top 34 (as shown in Fig. 3) leaving it well wound above the end 42 of the flask. The cap 44 is now screwed into place causing the surplus material 48 to exude from the openings 47, after the main body of the material is tightly compressed around the teeth 21 and the wax of the trial plate 20. The surplus material 48 is then removed and the entire flask subjected to heat and the wax of the trial plate 20 removed by well known methods after the flask has been separated by the unlocking of the ring 22.

It will be noted that the teeth 21 have become lodged in the material 48 while the wax portion 20 of the trial plate 20 is removed. In its place is now inserted a blank 54 (as shown in Fig. 5). Heat is now applied by any convenient means to soften the blank 54 and pressure is applied to force the material in the blank into the space previously occupied by the wax of the trial plate 20.

When the upper and lower parts of the mold are in engagement the locking ring 22 is turned to hold the halves of the flask together, after which the flask can be removed to a curing compartment leaving the press free for other operations and thereby encouraging the operator to fully cure the product instead of encouraging under-curing in order to regain the use of the press, as is now the common practice.

It is highly desirable to coat the interior of the flask with a polished chromium plate which greatly expedites the removal of the plastic materials therefrom.

I claim:

1. A dental flask having in combination a circular receptacle having parallel openings formed in its outer wall, equi-distant from and parallel to its axis, an upper flask portion comprising a tapering ring whose interior is substantially the same shape and size as is the interior of the receptacle, said ring having tapering posts disposed around the wide end thereof adapted to register with the holes in said bottom portion, each of said posts having notches formed on the inner and outer sides thereof, a locking ring associated with said bottom portion and rotatable with relation thereto having keyhole slots formed therein the large portion of which will receive the heads of said posts and the portion of said posts between 20 said notches passing freely through the narrow portion of said keyhole slots, and a cap removably secured to said upper flask portion by means of a fractional thread, said bottom portion, locking ring and cap having out-turned projections 25 formed thereon adapted to facilitate the relative rotation thereof.

2. The substance of claim 1, said locking ring having the portion thereof on the outside of said keyhole slots inclined to exert a wedging action 30 against said posts when said ring is rotated.

JULIUS J. E. BAUMGARTEN.
